UNITED STATES PATENT OFFICE.

HENRY L. PITMAN, OF WESTFIELD, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed June 4, 1923. Serial No. 643,165.

This invention relates to typewriting machines wherein a motor is employed for returning the carriage. More particularly, the invention is concerned with the motor 5 and transmission gear connections and support.

The invention is illustrated as applied to a machine in which the carriage-returning motor and controlling means therefor are 10 generally similar to those disclosed in my pending application No. 621,520, filed February 27, 1923 (now Patent No. 1,580,326, dated April 13, 1926). In that machine, the carriage-returning mechanism comprises 15 two separable units, each removably mounted at the back of the machine, viz, a motor-unit including the motor and motor-shaft, and a transmission-assembly unit. The latter unit includes a transmission-shaft separably connected to the motor-shaft, a pinion, a pinion-shaft, suitable gearing connecting said transmission and pinion shafts for driving the pinion-shaft, complementary 20 clutch-members on the pinion-shaft for connecting and disconnecting the pinion and the transmission mechanism, and a bracket removably mounted on the machine-frame for carrying the entire unit. The pinion meshes with a rack on the carriage and 25 drives it, when connected with the motor, to move the carriage in an anti-letter-feed direction.

Due to variations which may occur in the manufacture of the rather numerous parts 30 of the transmission-assembly, the carriage-return rack, and the supporting means for the rack, difficulty is sometimes experienced in causing the pinion and the rack to mesh properly when placed in the machine. In 35 accordance with the present invention in its preferred form, the transmission-assembly-supporting bracket is mounted on the machine-frame with provision for pivotal adjustment about an axis parallel to the pinion-shaft. This adjustment enables the pinion to be raised or lowered and so to be 40 engaged properly with the rack, but does not permit the pinion-teeth to be moved out of parallelism with the rack-teeth nor the direction of the pinion-shaft to be changed to cause interference with the shifting of the clutch. The adjustable bracket may 45 comprise a vertical portion pivoted on a bearing member received in the rear face of the machine-frame and a horizontal por-

tion having set-screws for engaging an upper horizontal face of the machine-frame, to finely adjust the bracket in opposite directions with reference to its pivot. Means 50 may also be provided for securing the bracket to the rear wall of the machine-frame in adjusted position.

The motor is mounted on the machine-frame independently of the transmission-assembly, and as a separate unit. The end 60 of the motor-shaft fits into the end of the transmission-shaft when the machine is completely assembled for operation. The adjustment of the transmission-assembly-supporting bracket, in assembling the machine, is apt to displace the end of the transmission-assembly shaft, however, and, in order that the connection may be made 65 between the motor and the transmission shafts in any adjusted position of the latter, the motor is also mounted upon an adjustable bracket. This bracket extends forward 70 horizontally over the base of the escapement-supporting frame located substantially at the middle of the back of the machine, and is held to said base by securing screws. Adjustment set-screws in the bracket bear against the supporting frame 75 and may be adjusted to raise or lower the bracket. The securing screws may be selectively turned to vary the limiting position 80 to which the bracket may be raised by the adjustment set-screws. The bracket, when thus adjusted and secured in place by the oppositely-acting adjustment and securing 85 screws, will have no tendency to become loose or to vibrate. In this way, advantage 90 is taken of the presence in the machine of a broad horizontal support upon which the motor may be adjustably mounted by means 95 which retain it securely in position. The mounting of the motor at the middle of the back has other advantages. The transmission-shaft may be made very short, thereby 100 reducing the amount that its free end is moved by adjustment of the transmission-assembly, and consequently reducing the amount which it is necessary to adjust the motor. The motor is located at one side 105 of the spring-drum-adjusting means, and this has the double advantage of rendering said means accessible and of permitting the motor to be set forward with its forward end extending into the machine-frame.

The arrangement of the parts is compact, 110

and the motor, when in operative position, prevents access to the adjustment and securing screws of the motor-supporting bracket, so that unintentional disturbance of the adjustment and securing screws is prevented. To facilitate mounting of the motor in the present compact assembly, the motor is made disconnectible at its lower end from its supporting bracket. The motor casing and bracket may be provided with openings arranged to be aligned and to receive securing bolts. Provision is also made for preventing rotation of the motor about the axis of the bolts. In assembling the carriage-returning mechanism in the machine, the transmission-assembly is first mounted on the frame, and its supporting bracket is adjusted to cause the pinion to mesh properly with the carriage-returning rack. The motor-supporting bracket, without the motor, is then secured in a tentative position on the frame. The end of the motor-shaft is placed in the socket of the transmission-shaft and the motor is swung down to enable the operator to see whether it is properly located to be attached to its supporting bracket. If the motor and bracket do not properly align, the motor may then be removed, the bracket may be adjusted, and the accuracy of the adjustment may be tested by again fitting the motor in place until the proper adjustment of the bracket has been attained, to permit the motor to be secured in operative position. The adjustment and securing screws, while they act oppositely to each other, are however both accessible from above, and this facilitates their operation.

Other features and advantages will hereinafter appear.

In the accompanying drawings,

Figure 1 is a rear elevation, partly broken away, of an Underwood typewriting machine embodying the improvements of the present invention.

Figure 2 is a perspective sectional side elevation of the machine.

Figure 3 is a detail horizontal sectional view on a larger scale than Figure 1, showing the motor-supporting bracket.

The typewriting machine comprises a frame 10, a carriage 11 movable in letter-feed direction by a spring-drum 12 under the influence of suitable escapement mechanism comprising a universal bar 13 in the paths of type-bars 14, a dog-rocker 15, an escapement-pinion 16 and an escapement-rack 17. The carriage is rapidly returned to the beginning of a line by a motor 18, made effective by motor-controlling means similar to those disclosed in the patent to Frederick A. Hart, No. 1,238,908, dated September 4, 1917. Such return operation may be initiated either by manually or automatically actuated means (not shown herein),

either of which is effective, when actuated, to move an arm 19 rearwardly, thereby rocking a shaft 20, which, through crank-arm 21, operates connections to close a motor-switch (not shown). The rocking of the shaft 20 is also effective through an arm 22, link 23, rock-arm 24, shaft 25 and arm 26 which extends into an annular groove 27 of a carriage-returning pinion 28, to move the pinion along its shaft 29 and cause a clutch-member 30, carried by the pinion, to engage with a complementary clutch-member 31 fast to the shaft 29, thereby connecting the pinion with the motor. The pinion 28 is always in mesh with a rack 32 on the carriage 11, and moves it, when rotated by the motor, to return the carriage. The motor 18 and its connections to the carriage-returning rack are made as two separable units, each removably mounted on the back of the machine-frame. One of these units is a transmission-assembly unit 33 comprising a worm-gear 34 on the rear end of the pinion-shaft 29, a worm 35 meshing with the gear 34 at the bottom thereof, and a horizontal worm-carrying transmission-shaft 36 extending parallel to the back of the machine. The transmission-assembly unit 33 also includes a gear-housing 37, having a flange 38 secured by screws 39 upon a vertical portion of a supporting bracket 40. The supporting bracket 40 is pivotally mounted upon a shouldered bearing-screw 41, which extends parallel to the pinion-shaft 29 and is threaded into the rear vertical face of the machine-frame 10. The supporting bracket 40 has a horizontal flange 42 which extends forward over a horizontal surface 43 of the machine-frame 10. Two set-screws 44 are threaded into the horizontal flange 42 and bear upon the horizontal surface 43 just in front of the tabulator-frame 45 and behind the rear carriage-supporting rail 46 for adjusting the bracket about its pivot. The carriage 11 may be moved to the left (as viewed by the operator) to clear this portion of the frame, and a screw-driver may be conveniently inserted between the rail 46 and tabulator-frame 45 to adjust the set-screws 44. The bracket 40 may then be secured firmly in adjusted position by tightening a nut 47 upon a bolt 48 which passes through the rear wall of the machine-frame and through an opening in the vertical portion of the bracket 40 that is large enough to permit the adjustment of the bracket.

The transmission-shaft 36 has a sleeve 49 fast upon it, which extends beyond the end of the shaft and forms a socket 50 for loosely receiving the end of the motor-shaft 51. A driving connection between said motor and transmission shafts is effected through a pin 52 on the motor-shaft and a slot 53 in the sleeve 49. The tilting of the transmission-assembly 33 about the piv-

ot-screw 41 to adjust the pinion 28 up and down will, of course, raise and lower the socket 50 which is to receive the motor-shaft 51. Provision is therefore made of means for adjusting the motor to permit a connection to be effected between the ends of the transmission and motor shafts 36 and 51 in any adjusted position of the former. A motor-supporting bracket 54 is held upon the base 55 of the escapement-mechanism-supporting frame 56 by four headed securing screws 57 which pass freely through the bracket 54 and are threaded into the base 55. Two adjustment set-screws 58 are threaded into the bracket 54 and engage the upper face of the base 55. The bracket 54 is adjusted by selectively turning the screws 57 to limit the upward movement of the bracket in the desired position, and by then turning the set-screws 58 to raise the bracket and press it forcibly against the heads of said screws 57. It will be seen that the bracket may be raised or lowered bodily or tilted in any direction to locate the motor-shaft 51 in the position required.

The motor, when operatively positioned, extends forward into the machine-frame so that the dimensions of the machine are increased very little by the addition of the motor. The arrangement of the mechanism is compact, and the motor, when secured in place upon the bracket, prevents access to the adjusting screws 57 and 58. Unintentional disturbance of the adjustment screws 58 is thus prevented by their normal concealment forward of the motor-casing 59. The motor-casing 59 is made separable from the supporting bracket 54, so that the motor may be removed during adjustment of the bracket 54 and may thereafter be secured in position. The motor-casing 59 is provided with ears 60 at its lower end, which have aligned openings 61 through which bolts 62 and 63 may be passed for securing the motor to the bracket 54. The bolt 62 has a lock-nut 62^a threaded upon it between the ear 60 and the bracket 54, which may be tightened against the bracket to prevent relative rotation of the motor-casing 59 and the bracket. In assembling the machine, the transmission-assembly unit 33 is first adjusted and secured in place. The motor-supporting bracket 54 without the motor is then tentatively secured in position by the screws 57 and 58. The end of the motor-shaft 51 is then inserted in the socket 50 and the motor is swung down to enable the operator to see whether the bolts 62 and 63 can be inserted for securing the motor to the bracket 54, and, if they cannot be inserted, to see how much the motor-supporting bracket will have to be adjusted. The motor is then removed, any required adjustment of the bracket 54 is made, and the accuracy of

the adjustment is tested if necessary until the required adjustment of the bracket is obtained, whereupon the motor is rigidly secured to the bracket.

The carriage-propelling spring-drum 12 is adjusted by a knob 64 through connections which may be like those disclosed in the patent to William F. Helmond, No. 1,442,880, dated January 23, 1923. The electrical connection box 65 is mounted on the machine-frame 10 directly behind the spring-drum 12, but is low enough not to interfere with the adjustment of the knob 64. The motor is mounted at one side of the knob 64 and so avoids interference with the knob.

Should it be desired to remove the transmission-assembly 33 for repairs, this may be done without removing the motor and without losing the benefit of the adjustment of bracket 40, by withdrawing the screws 39 that connect the transmission-assembly to the bracket 40.

Variations may be resorted to within the scope of the invention, and portions of the improvements may be used without others.

Having thus described my invention, I claim:

1. In a typewriting machine, a main typewriter framework, including a base, a carriage, carriage-returning mechanism comprising a rack on the carriage, a pinion in mesh with the rack, and means for driving the pinion consisting of a motor-unit which includes a motor-shaft, and a transmission-unit which includes transmission and pinion shafts and gearing connecting said shafts, a bracket supporting the transmission-unit on the back of the machine-frame, means for adjusting said bracket to raise or lower the pinion to engage it properly with the rack on the carriage, a horizontal forwardly-extending bracket supporting the motor-unit on said typewriter base, and means for adjusting the motor-supporting bracket so that the motor-shaft may be connected properly to the end of the transmission-shaft.

2. In a typewriting machine, a main typewriter framework, including a base, a carriage, a carriage-returning mechanism comprising a rack on the carriage, a pinion in mesh with the rack, and means for driving the pinion consisting of a motor-unit which includes a motor-shaft, and a transmission-unit which includes transmission and pinion shafts and gearing connecting said shafts, the transmission-shaft having a socket and the motor-shaft having its end received in said socket, a bracket supporting the transmission-unit on the back of the machine-frame at one side thereof, means for adjusting said bracket about an axis parallel to the pinion-shaft to raise and lower the transmission-unit to engage the pinion properly with the rack on the carriage, a horizontal

forwardly-extending bracket supporting the motor-unit on said typewriter base, and means for adjusting the motor-supporting bracket comprising securing screws for limiting the separation of the bracket and frame, and set-screws for raising the bracket away from the frame.

3. In a typewriting machine, a frame comprising a horizontally-extending base portion at the middle of the back of the machine, a carriage, carriage-returning mechanism comprising a rack on the carriage, a pinion in mesh with the rack, and means for driving the pinion consisting of a motor-unit which includes a motor-shaft, and a transmission-unit which includes transmission and pinion shafts and gearing connecting said shafts, the transmission-shaft having a socket for receiving the end of the motor-shaft, means for adjusting the transmission-unit to cause the pinion to mesh properly with the rack, a horizontal forwardly-extending bracket supporting the motor-unit on the base portion of the frame at the middle of the back of the machine, means for adjusting the motor-supporting bracket to enable a connection to be made between the motor and transmission shafts, said adjusting means being inaccessible when the motor is in position on the bracket, and means for disconnectably securing the motor to the bracket, so that the motor may be removed from the bracket during adjustment of the bracket and, after adjustment, the end of the motor-shaft may be inserted endwise in the socket of the transmission-shaft and the motor may be swung down and secured to the bracket.

4. In a typewriting machine, a frame, a carriage, carriage-returning mechanism comprising a rack on the carriage, a pinion in mesh with the rack, and means for driving the pinion consisting of a motor-unit and a transmission-unit, a transmission-unit support, means for adjusting the transmission-unit support to adjust the pinion relatively to the rack, a motor-unit support, means for adjusting said support to adjust the motor with reference to the transmission-unit, and means separably connecting the transmission-unit and its support whereby the transmission-unit may be removed from the machine independently of its support and of the motor-unit and may be replaced without again adjusting the transmission-unit support and the motor support.

5. In a typewriting machine, a frame, a carriage, carriage-returning mechanism comprising a rack on the carriage, a pinion in mesh with the rack, and means for driving the pinion consisting of a motor-unit and a transmission-unit, a transmission-unit support, means for adjusting said support to cause the pinion to mesh properly with the rack, a motor-unit support, means for

adjusting the motor-unit support to fit the motor in the machine relatively to the transmission-unit, and means separably connecting said units to their respective supports, so that either or both of the units may be removed from the machine independently of the supports and may thereafter be replaced in their previously-determined adjusted relationships.

6. In a typewriting machine, a frame, a carriage, carriage-propelling means comprising a spring-drum and adjusting means therefor at one side of the back of the machine, compact carriage-returning means comprising a motor and a transmission-unit connecting the motor and carriage, means for supporting the transmission unit on the back of the machine at one side thereof, and means for supporting the motor on the back of the machine at the middle thereof with the forward end of the motor extending within the machine-frame, the arrangement being such that the spring-drum-adjusting means may be manipulated by the operator with the motor in operative position.

7. In a typewriting machine, a frame, a carriage, carriage-propelling means comprising a spring-drum and an adjusting knob therefor at one side of the machine and substantially flush with the back of the frame, compact carriage-returning means comprising a motor and transmission mechanism connecting the motor and carriage, means for supporting the transmission mechanism at one side of the back of the frame, and means for supporting the motor on the back of the machine-frame at one side of the spring-drum-adjusting knob with the forward end of the motor located within the machine frame.

8. In a typewriting machine, a frame, a traveling carriage, carriage-returning mechanism comprising a rack on the carriage, a pinion meshing with the rack, a motor and a transmission-assembly unit to connect the motor and pinion and including a forwardly-extending pinion-shaft, a bracket supporting the entire transmission-assembly unit on the back of the machine-frame at one side thereof, said bracket having a vertical portion, a pivotal support on the rear vertical portion of the machine-frame for said bracket, the axis of the pivotal support being parallel to the pinion-shaft, the bracket also comprising a horizontal portion extending forwardly over a horizontal surface of an end portion of the machine-frame, set-screws in the horizontal portion of the bracket, in a position to be rendered accessible by movement of the carriage, for adjusting the bracket in opposite directions about its pivot to adjust the carriage-returning pinion up and down with reference to the carriage-returning rack, and means for securing the vertical portion of the bracket firmly to the back of the ma-

chine-frame to prevent vibration in operation.

9. In a typewriting machine, a frame, a traveling carriage, carriage-returning mechanism comprising a rack on the carriage, a pinion meshing with said rack, a motor and a transmission-assembly unit to operatively connect the motor and pinion and comprising a forwardly-extending pinion-shaft, a bracket supporting the transmission-assembly unit on the back of the machine-frame at one side thereof for pivotal movement about an axis parallel to the pinion-shaft, means movable substantial distances for adjusting the transmission-assembly-supporting bracket through relatively minute distances to cause the pinion to be adjusted into co-operative relationship with the carriage-returning rack, and means for securing the bracket against vibration in adjusted position.

10. In a typewriting machine, a frame, a traveling carriage, carriage-returning mechanism comprising a rack on the carriage, a pinion meshing with said rack, a motor and a transmission-assembly unit supporting the pinion to connect the motor and pinion, micrometric adjusting means for adjusting the pinion up and down to engage it properly with the rack, and means for firmly securing the adjusted position of the pinion.

11. In a typewriting machine, a frame, a traveling carriage, carriage-returning mechanism comprising a rack on the carriage and a pinion for driving said rack, pinion-supporting means on the machine-frame, micrometric adjusting means for said supporting means to raise and lower the pinion to engage it properly with the rack, and means for fixing the pinion-support securely against vibration in adjusted position.

12. In a typewriting machine, a frame, a traveling carriage, carriage-returning mechanism comprising a rack on the carriage and a pinion for driving said rack, pinion-supporting means on the machine-frame, and means for adjusting the pinion-supporting

means to raise and lower the pinion to engage it properly with the rack, said adjusting means being inherently incapable of alteration by force exerted upon the pinion-support.

13. In a typewriting machine, the combination with a typewriter framework including a base, and a carriage, of power mechanism for returning the same, including a motor, a support therefor, and means for mounting said support upon said base, including devices adjustable for securing fine variations in the position of the motor, said motor mounted for movement on said support into and out of working position, means for fastening the motor upon said support in working position, said carriage-returning mechanism also including transmission mechanism, a bracket whereby said transmission mechanism is mounted upon said framework, and means for effecting fine adjustments of said bracket independently of said motor support.

14. In a typewriting machine, the combination with a typewriter framework including a base, and a carriage, of power mechanism for returning the same, including a motor, a support for said motor, a transmission mechanism between said motor and said carriage, a bracket for supporting said transmission mechanism upon said framework, and means for effecting fine adjustments of said bracket relatively to said support.

15. In a typewriting machine, the combination with a typewriter framework including a base, and a carriage, of power mechanism for returning the same, including a motor, a support for said motor, a transmission mechanism between said motor and said carriage, a bracket for supporting said transmission mechanism upon said framework, and means for effecting fine adjustments of said bracket relatively to said support, said motor being mounted upon said support for movement out of and into working position.

HENRY L. PITMAN.
